UNITED STATES PATENT OFFICE

JEAN D. SEGUY, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS OF TREATING HYDROCARBON OIL

Application filed December 19, 1928. Serial No. 327,004.

This invention relates to improvements in process of treating hydrocarbon oil, and is more particularly directed to the cracking of such hydrocarbon oils as petroleum for the production therefrom of gasoline or other light hydrocarbons.

This invention is more particularly directed to that type of cracking process in which the oil may be passed through a heating tube, then to an expansion chamber, the vapors removed and subjected to dephlegmation, and the reflux condensate recracked. The residuum in such type of process is drawn out of the expansion chamber.

15 In processes of this type, particularly in handling heavy oils or other oils tending to produce substantial quantities of coke and sludge, difficulty may be experienced in getting a high yield of gasoline and at the same 20 time producing a marketable residuum.

The object of this invention is to obtain from the process a desired yield of gasoline, while at the same time limiting and possibly preventing the formation of an objectionable 25 amount of coke and sludge in said residuum.

To this end, the liquid products or residue separated from the vapors are continuously withdrawn from the system in such a manner that they remain in the reacting zone 30 only for a minimum length of time, depending upon the characteristics of the oil undergoing treatment, thus avoiding as far as possible, objectionable formation of coke, sludge, and the like due to extended retention of this 35 liquid residuum at high temperature. The time limit during which the liquid residuum should remain in the expansion chamber at high temperature is dependent upon the type of oil treated and the extent to which it 40 is desired to limit the formation of sludge and coke and the like, and it is controlled by the height to which the residue is permitted to accumulate in the expansion chamber and by the rate of withdrawal of said residue 45 therefrom. For a given time limit, this height is dependent upon the size of the separating or expansion zone, the rate of feed of the material through the apparatus, and the pressures, and temperatures used.

50 As a further object of the invention, the

liquid residue is continuously withdrawn from the expansion or separating zone at such a rate that it remains in said zone for the desired length of time, and thereafter is immediately partially cooled as it is withdrawn from the zone and flashed under reduced pressure, and the flashed vapors may be subjected to dephlegmation.

The residuum withdrawn from the high pressure separating zone is cooled, not only by flashing, but before being subjected to flashing it is preferably cooled by admixture in direct physical contact therewith of a suitable cooling agent, preferably the mixture of hydrocarbon products from cracking which goes by the name of pressure distillate bottoms and which, in a process of the character described, is a cut intermediate the reflux condensate and the end point gasoline produced and which in the trade would correspond to heavy naphtha kerosene fractions. This cut may cover a boiling point range between about 400 and 600° F., more or less.

The primary cooling by direct heat interchange and the subsequent cooling due to 75 flashing, arrest any reaction that may tend to proceed in the residual products after they are withdrawn from the high temperature zone, thereby preventing the formation of objectionable amounts of sludge and coke.

The temperature to which the residual products withdrawn from the high temperature zone may be cooled by controlled heat interchange before being subjected to flashing, must be properly balanced with the 85 degree of reduction of pressure which they undergo during flashing, so as to produce the desirable total cooling effect, as well as the desired degree of vaporization of the lighter portion of the residual products withdrawn 90 from the high temperature zone.

Other features of the invention will be apparent from the following description of the process according to the invention:

In the accompanying drawing, I show an 95 apparatus suitable for carrying out the present invention, it being understood that this is merely a diagrammatic showing and in no sense drawn to scale.

Referring to the drawing, 1 designates a 100

conventional type furnace in which is mounted the heating tube 2, provided with a transfer line 3, having a throttle valve 4 and leading to the reaction or vapor separating or expansion chamber 5. The vapors separated therein pass out of the reaction chamber through line 6, having throttle valve 7 to the side of the dephlegmator 8. From the top of the dephlegmator, the uncondensed vapors 10 pass through line 9 to condenser coil 10 and thence to receiver 11. This receiver has gas control valve 12 and distillate control valve 13 for the discharge of these respective products. The reflux formed in the dephlegmator 8 may be returned to the heating coil 2 by line 14 and hot oil pump 15. Raw oil 15 may be fed directly to the heating coil 2 by means of feed pump 16 and into line 14 where it combines with the reflux.

20 The residual liquid products from the reaction zone are continuously withdrawn through the draw-off pipe 18 connected to the bottom of the chamber 5. The rate of withdrawal is controlled in a suitable manner, 25 depending upon the conditions of the operation to maintain in chamber 5 such liquid level as will provide for the desired time element during which the residual liquid products may remain in the high temperature 30 zone 5 without becoming laden with objectionable quantities of sludge and coke.

Additional side draw-offs 18' are shown but should only be used after bottom draw-off 18 has become clogged, although the latter draw-off should be used, if possible, alone during the operation, particularly when the level which must be obtained in chamber 5 is relatively low. The residual liquid products withdrawn from chamber 5 through pipe 18 40 in which is interposed valve 19 are passed to line 20, in which is interposed valve 21 and into flash chamber 22.

As a feature of the invention, the residual liquid products from chamber 5 are mixed 45 during their passage from chamber 5 to flash chamber 22 with a suitable quantity of so-called pressure distillate bottoms, introduced into line 20 through branch 23, controlled by valve 24.

50 Before being introduced into the system, the supply of pressure distillate bottoms may be brought to the desired temperature by either heating or cooling by suitable means (not shown) so that, by a proper control of 55 the temperature and quantity of said pressure distillate bottoms introduced, the mixture of pressure distillate bottoms and residual products from chamber 5 may be partially cooled to a suitable temperature below the temperature 60 at which objectionable extended reaction proceeds. The temperature and amount of the pressure distillate bottoms introduced in line 20 depends not only upon the temperature to which it is desired to cool the un- 65 vaporized products from chamber 5, but it

also depends upon the characteristics of the products desired from the process, particularly upon the viscosity, flash and fire points, and other characteristics which may be specified for the residuum to be produced by the 70 process.

At the same time as a supply of cooling agent, to wit:—pressure distillate bottoms, is introduced from line 23 into the residual products from chamber 5 and in direct physical contact therewith, an additional reduction in temperature of these residual products is obtained by reduction of pressure, such as to cause flash distillation in chamber 22. This reduction of pressure may be effected by the regulation of either or both of the valves 19 or 21, depending upon whether it is desired to introduce the pressure distillate bottoms before or after the pressure has been reduced on the unvaporized liquid products with which 75 said pressure distillate bottoms are to be admixed.

80 Partial vaporization of the mixture is effected in the flash chamber 22 and the degree of vaporization is dependent upon the degree of total cooling due to the partial cooling resulting from the admixture of pressure distillate bottoms and the partial cooling resulting from the reduction in pressure.

85 The degree of vaporization in chamber 22 90 may also be controlled or helped by introduction of steam or other heated gas into chamber 22 or by mildly heating said chamber.

95 The unvaporized residue from chamber 22 100 is withdrawn therefrom through line 25, controlled by valve 26, and thence cooled, stored, or sent for further treatment. The vapors released in the flash chamber 22 may be passed through line 27, controlled by valve 105 28, condensed in condenser 29 and collected in receiver 30, or these vapors may be passed through branch 31, controlled by valve 32, and directed to a dephlegmator 33 from 110 which uncondensed vapors pass to line 27 through branch 34, controlled by valve 35, and from which condensate may be withdrawn through line 36 and directed to storage or taken by hot oil pump 37 and returned through line 38 into the dephlegmator 115 8 from which it is returned to the system for further treatment.

120 Raw oil or other cooling medium, may be introduced to dephlegmators 8 and 33 in a suitable manner.

125 The pressure distillate bottoms used in the process to partially cool the unvaporized products from the cracking reaction before they are subjected to flashing may be a product of the same operation or of a previous operation of the process, depending upon the degree of fractionation to which the vapors produced in the process are subjected before collection.

130 In the method of carrying out the inven-

tion illustrated in the drawing, the pressure distillate bottoms introduced from line 23 will generally result from the re-distillation of the pressure distillate collected in the receiver 13 after dephlegmation of the vapors in dephlegmator 8. In general practice and in carrying out a process of the character described, the vapors leaving the dephlegmator 8 have an end point higher than the 10 end point of gasoline, and it is necessary to subject these vapors after condensation and collection as pressure distillate to distillation for separation of the gasoline. The residue from such distillation, generally called 15 pressure distillate bottoms, is the product used as described in the process of this invention.

As another method to carry out the invention, the vapors leaving the dephlegmator, 20 instead of being condensed and collected as such and as pressure distillate, may be subjected to additional dephlegmation in a secondary dephlegmator (not shown) whereby said vapors are separated without additional 25 distillation into end point gasoline vapors and condensed pressure distillate bottoms. The end point gasoline vapors are then condensed and collected as shown, and the pressure distillate bottoms produced from 30 said secondary dephlegmator may then be used alone, or in admixture with pressure distillate bottoms from other sources, to cool the unvaporized liquid products removed from chamber 5 in the manner heretofore 35 described.

When the process is carried out along the alternative method just described, the pressure distillate bottom return line connecting the bottom of the secondary dephlegmator to 40 the draw-off line 18 from chamber 5 may comprise branches and by-pass permitting the regulation of the amount of pressure distillate bottoms returned to the system through line 23 and by-passes on which may 45 be interposed coolers, heaters, and hot oil pumps to permit the control of the temperature at which the pressure distillate bottoms are to be admixed with the unvaporized liquid products from chamber 5 and the pressure 50 under which they are to be charged into the line 18.

In the event such a method is carried out where pressure distillate bottoms are produced in the process by means of a secondary 55 dephlegmator (not shown) the condensate formed in dephlegmator 33, instead of returning to the dephlegmator 8, as shown in the drawing, may be returned to the secondary dephlegmator (not shown) in toto or in part 60 to both the primary dephlegmator 8 and the secondary dephlegmator (not shown).

Among the advantages of the process herein described is the fact that the admixture 65 of the pressure distillate bottoms with the unvaporized products from the high tem-

perature cracking zone arrests rapidly any extended cracking of said products, and that a relatively small quantity of pressure distillate bottoms is generally sufficient to produce a relatively large cooling on account of 70 the relatively low boiling point of these pressure distillate bottoms compared with the boiling point of the unvaporized products from chamber 5 and on account of the high latent heat of vaporization of said pressure 75 distillate bottoms.

As another advantage, the pressure distillate bottoms help to dissolve sludge which may have been formed in the unvaporized products from reaction chamber 5. This reduces the viscosity of these products, and it helps avoiding clogging of the residuum draw-off lines which may occur on account of the high viscosity of unvaporized products resulting from the treatment of certain oils, 85 even though said products contain less than 2% sludge or thereabouts. In other words, depending upon the characteristics of the oil treated, the unvaporized products withdrawn from the chamber 5 and containing about 2% 90 sludge or coke may have viscosities ranging from, say 100 to 1000 seconds Saybolt furol, even though the cracking reaction has been limited to the extent that will produce about 2% sludge or less in every case. Admixture 95 of said unvaporized products with pressure distillate bottoms produces the desired cooling effect at the same time as it reduces the viscosity.

As another advantage, pressure distillate 100 bottoms resulting from processes of the character heretofore described, may contain some light fractions which, if separated, might well come within the range of boiling points of gasoline fractions. The admixture of 105 these pressure distillate bottoms with the unvaporized products and the flashing of the mixture thereafter permits vaporization of such portions of the pressure distillate bottoms as are herein referred to and they are 110 further recovered after cooling and condensation.

Another advantage consists in that the admixture of these pressure distillate bottoms with the heavier unvaporized liquid products from the reaction tends to lower the vapor pressure of the products undergoing flashing, which results in a larger amount of distillate carried over at a definite temperature, therefore resulting in an easier control 115 of the degree of vaporization in chamber 22, and overcoming, to some extent, the reduction in degree of vaporization resulting from reduction of temperature due to the admixture of said pressure distillate bottoms with 120 the residues from the chamber 5.

As an illustration of a method to carry out the invention, California oil having a gravity of about 19° B. may be heated in coil 2 to a temperature of about 900° F. under a pres- 130

sure of about 150 pounds. The unvaporized products are withdrawn from the chamber 5 at such a rate that no more than about 65 to 85 cubic feet of liquid is permitted to accumulate therein. These products withdrawn from chamber 8 at a temperature of about 800° F. are cooled by admixture with about 10 to 30% of pressure distillate bottoms resulting in a partial cooling of the mixture to a temperature of from 400 to 500° F., after which the pressure may be reduced from 150 pounds down to about 20 to 25 pounds, or less.

Distillation in the flash chamber 23 is so controlled by injection of steam that the viscosity of the residuum withdrawn from the bottom of said chamber 23 is maintained below 500 seconds Saybolt furol, at 122° F., and the flash point at about 150° F., with a coke and sludge content of less than 2% measured by benzol centrifuge.

In this operation about 40 to 45% of 437° F. end point gasoline is produced based on the charge, and about 35% of the residuum, having characteristics heretofore described, is withdrawn from the flash chamber 23.

I claim as my invention:

1. A process of cracking hydrocarbon oil, comprising subjecting the oil to cracking temperature under pressure, thereafter separating the vapors from non-vaporous residue, removing, condensing and collecting the vapors, removing the liquid residue from the cracking zone before it contains objectionable amounts of sludge and coke, and admixing with said residue a quantity of pressure distillate bottoms so controlled as to amount and temperature as to cool said residue to below cracking temperature, thereafter reducing the pressure on the mixture of residue and pressure distillate bottoms so as to cause partial vaporization thereof and additional partial cooling.
2. A process of cracking hydrocarbon oil, comprising subjecting the oil to cracking temperature under superatmospheric pressure, thereafter separating the vapors from liquid residue, removing, condensing and collecting the vapors, removing the liquid residue from the cracking zone before it contains objectionable amounts of sludge and coke, admixing with said residue a controlled quantity of hydrocarbon oil distillate having a boiling point range between approximately 400 to 600° F., said distillate being in such amount and of such temperature as to cool said liquid residue to below cracking temperature, thereafter reducing the pressure on the mixture of residue and said oil distillate so as to cause partial vaporization and additional partial cooling.

In testimony whereof I affix my signature.
JEAN D. SEGUY.
